Filed Oct. 12, 1972, Ser. No. 297,091

Term of patent 14 years

Int. Cl. D8—03, 99

U.S. Cl. D8—8

FIG. 1 is a front perspective view of a hand grip for an electric grass shear or similar article showing my new design, the broken lines representing the extension handle of an electric grass shear or similar article being shown for illustrative purposes only;

FIG. 2 is a side plan view thereof showing the side opposite that shown in FIG. 1;

FIG. 3 is a top plan view thereof;

FIG. 4 is a front elevational view thereof;

FIG. 5 is a rear elevational view thereof; and

FIG. 6 is a bottom plan view thereof.

I claim:

The ornamental design for a hand grip for an electric grass shear or similar article, as shown and described.
